(57) CLAIM

The ornamental design for an orthopaedic device as shown and described.

DESCRIPTION

FIG. 1 is a top plan view of the orthopaedic device showing the claimed design;

FIG. 2 is a right side view thereof;

FIG. 3 is a front view thereof;

FIG. 4 is a left side view thereof;

FIG. 5 is a rear view thereof; and,

FIG. 6 is a front perspective view thereof.
